CLAIM

The ornamental design of a dispensing container with pump, as shown and described.

DESCRIPTION

FIG. 1 is a front top perspective view showing the new invention of an ornamental design of a dispensing container with pump.

FIG. 2 is a front view of the invention.

FIG. 3 is a rear view of the invention.

FIG. 4 is a left side view of the invention.

FIG. 5 is a right side view of the invention.

FIG. 6 is a top view of the invention; and,

FIG. 7 is a bottom view of the invention.

Surface shading has been added in the drawing figures to show the character and contour of the surfaces of the design. The broken lines in the drawings depict portions of the dispensing container with pump that form no part of the claimed design.

1 Claim, 6 Drawing Sheets
